UNITED STATES PATENT OFFICE

155,131

DESIGN FOR A SUPPORTING BRACKET
OR THE LIKE

James E. Donaldson, Chicago, Ill.

Application December 13, 1946, Serial No. 135,489

Term of patent 14 years

(Cl. D33—3)

To all whom it may concern:

Be it known that I, James E. Donaldson, a citizen of the United States, residing at Chicago, in the county of Cook and State of Illinois, have invented a new, original, and ornamental Design for a Supporting Bracket or the like, of which the following is a specification, reference being had to the accompanying drawing, forming part thereof.

In the drawing:

Figure 1 is a perspective view of the outside of the supporting bracket in raised position, showing my new design;

Figure 2 is a rear elevational view of the same;

Figure 3 is a plan view of the same;

Figure 4 is a side elevational view of the same in open position; and

Figure 5 is a perspective view of the supporting bracket in lowered position.

I claim:

The ornamental design for a supporting bracket or the like, as shown.

JAMES E. DONALDSON.
